(57) **CLAIM**

We claim the ornamental design for a bone shaped portable
watering, feeding, and waste bag storing apparatus, as shown
and described.

DESCRIPTION

FIG. 1 is a front view of a bone shaped portable watering,
feeding, and waste bag storing apparatus in accordance with
the present invention;

FIG. 2 is a side view thereof;

FIG. 3 is a rear view thereof; and,

FIG. 4 is a front, side perspective of the bone shaped portable
watering, feeding, and waste bag storing apparatus in an
expanded condition.

The broken line showing of a waste bag in FIG. 1 is for
environmental context only and is not claimed.
